136,670

DESIGN FOR A COMPOUND TOOL

Tom Luke Leon, Portland, Oreg.

Application August 18, 1943, Serial No. 110,937

Term of patent 7 years

To all whom it may concern:

Be it known that I, Tom Luke Leon, a citizen of the United States, residing at Portland, in the county of Multnomah and State of Oregon, have invented a new, original, and ornamental Design for a Compound Tool, of which the following is a specification, reference being had to the accompanying drawing, forming part thereof.

Figure 1 is a front elevational view of a compound tool showing my new design.

Figure 2 is a top edge view thereof,
Figure 3 is a bottom edge view,
Figure 4 is a front end elevational view, and
Figure 5 is a rear end elevational view.

I claim:

The ornamental design for a compound tool, as shown.

TOM LUKE LEON.
